US0D1065723S

(12) **United States Design Patent** (10) **Patent No.:** **US D1,065,723 S**
(45) **Date of Patent:** **** Mar. 4, 2025**

(54) **CAT TOY**

(71) Applicant: **Yiwu Zhangkun Electronic Commerce Co., Ltd.**, Yiwu (CN)
(72) Inventor: **Kun Zhang**, Yiwu (CN)
(73) Assignee: **Yiwu Zhangkun Electronic Commerce Co., Ltd.**, Yiwu (CN)

(**) Term: **15 Years**

(21) Appl. No.: **29/853,360**

(22) Filed: **Sep. 15, 2022**

(51) LOC (15) Cl. **30-99**

(52) U.S. Cl.

USPC **D30/160**

(58) **Field of Classification Search**

USPC ..... D30/160, 199; 119/707-711, 51.01, 119/51.11, 51.13, 51.15; D21/713, 707, D21/505, 398, 386, 498, 479, 499; D14/233; D19/1, 61; 434/214, 278; 211/1; 273/155; 342/8; 428/66.5, 9; 446/199, 92, 85; 473/569; D3/271.1; D9/430, 651, 545, 611, 719, 516, 519, D9/520, 523, 525, 529, 544, 549, 414, D9/417, 428, 555, 503, 505, 454, 439, D9/744, 689, 682, 552, 564; D28/91.1, D28/82, 80, 76, 89, 79; D26/42, 49 CPC A01K 5/02; A01K 5/0233; A01K 5/0241; A01K 5/025; A01K 5/0275; A01K 5/0283; A01K 5/0291; A01K 15/00; A01K 15/02; A01K 15/021; A01K 15/025; A01K 15/026; A01K 15/027; A01K 13/00; A01K 13/001-003

CLAIM

The ornamental design for a cat toy as shown and described.

DESCRIPTION

FIG. 1 is a perspective view of a cat toy, showing my new design;

FIG. 2 is another perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof; and,

FIG. 9 is a partial enlarged view of FIG. 2.

The broken lines in the figures are for the purposes of illustrating portions of the cat toy, which form no part of the claimed design.

1 Claim, 8 Drawing Sheets
